US00D940817S

(12) **United States Design Patent** (10) Patent No.: **US D940,817 S**
Kordus et al. (45) Date of Patent: ** Jan. 11, 2022

(54) **INSECT TRAP**

(71) Applicant: **BioGents AG**, Regensburg (DE)

(72) Inventors: **Armin Kordus**, Regensburg (DE);
Christian Müller, Regensburg (DE)

(**) Term: **15 Years**

(21) Appl. No.: **35/510,867**

(22) Filed: **Jun. 4, 2020**

(80) **Hague Agreement Data**

Int. Filing Date: **Jun. 4, 2020**

Int. Reg. No.: **DM/208872**

Int. Reg. Date: **Jun. 4, 2020**

Int. Reg. Pub. Date: **Dec. 4, 2020**

(51) **LOC (13) Cl. 22-06**

(52) **U.S. Cl.**

USPC **D22/122**

(58) **Field of Classification Search**

USPC D22/119, 120, 122, 123, 124

CPC A01M 3/02; A01M 3/022; A01M 3/025;

A01M 3/04

See application file for complete search history.
